(57) CLAIM

The ornamental design for an automobile, as shown and described.

DESCRIPTION

FIG. 1 is a top, front and left perspective view of an automobile showing our new design;

FIG. 2 is a top, rear and right side perspective view thereof;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is a top plan view thereof.

The bottom view is omitted and unornamented.

The broken line portions show unclaimed subject matter only and form no part of the claimed design.

1 Claim, 7 Drawing Sheets

FIG. 3

FIG. 5

FIG. 6

FIG. 7
